(57) **CLAIM**

The ornamental design for a camera, as shown and described.

DESCRIPTION

FIG. 1 is a front and left side perspective view of a camera showing our new design;

FIG. 2 is a front elevational view of the camera illustrated in FIG. 1;

FIG. 3 is a rear elevational view of the camera illustrated in FIG. 1;

FIG. 4 is a left side elevational view of the camera illustrated in FIG. 1, the right side view being a mirror image of the left side view;

FIG. 5 is a top plan view of the camera illustrated in FIG. 1; and,

FIG. 6 is a bottom plan view of the camera illustrated in FIG. 1.

The portion of the article depicted in broken lines is for illustrative purposes only and forms no part of the claimed design. The thin solid lines illustrate contour.
